(No Model.)

H. COHENNO.
PERAMBULATOR.

No. 413,709.

Patented Oct. 29, 1889.

UNITED STATES PATENT OFFICE.

HENRY COHENNO, OF NEW YORK, N. Y.

PERAMBULATOR.

SPECIFICATION forming part of Letters Patent No. 413,709, dated October 29, 1889.

Application filed September 4, 1889. Serial No. 322,941. (No model.)

To all whom it may concern:

Be it known that I, HENRY COHENNO, of the city of New York, county of New York, State of New York, a citizen of the United States, have invented certain new and useful Improvements in Perambulators, of which the following is a full, clear, and exact description, reference being had to the accompanying drawings, forming part of this specification.

My invention relates to perambulators; and it consists in the combination of devices hereinafter described, and as more particularly recited in the claim, whereby the carriage-body and running-gear thereof are adapted to be folded together upon themselves, as hereinafter set forth.

Figure 1 is a side elevation of a perambulator containing my invention. Fig. 2 is a plan of the same. Fig. 3 is a plan of the side bars and axle-trees. Fig. 4 is an end view of the carriage-body. Fig. 5 is a similar view of the same, showing a modification of the joint which unites the body-sides; and Fig. 6 is a perspective view of the end of a uniting link or bar.

In carrying out my invention the carriage-body is formed of the two sides A A', mounted on the side bars B B', and preferably with the springs C C' interposed, as shown. The bottom of the body is composed of a piece or pieces D, hinged to the lower edge of the sides and adapted to fold to the inner face of the sides. When two pieces are used, as shown, they are united by tie-hooks d when unfolded horizontally to form the bottom. The side bars carry the laterally-projecting axle-trees b, and are united by cross-pieces b', which are pivoted to one of the side bars, and are detachably connected to the opposite bar, as shown. The sides A A' are united at their ends, front and rear, by bars a, which are pivoted to the side ends, and are pivoted or hinged together endwise, as at a', about midway between the sides, as shown. These bars a may be in the form shown in Fig. 4, consisting of

pairs of straight bars pivoted, respectively, to the sides A A' and reaching toward each other across the space between the sides and their free ends united by a hinge-joint a', as shown, said joint having the locking-finger a² on one bar adapted to engage the end of the other bar of the pair, and thus prevent the bars passing downward below a horizontal position when extended to hold the sides apart; or the bars a may be in the form of lazy-tongs, as shown in Fig. 5.

It is evident that when the carriage is in use the sides A A' may be held in position by the bars a and the side bars B B' of the running-gear held extended apart by the cross-piece b', and that when the carriage is not in use the bottom D may be folded upward to the sides A A', and by means of the linked bars a the sides A A' may be folded upward together flatwise, while the side bars B B' may be permitted to come together to accommodate the folding of the sides A A' by detaching the cross-pieces b' from the bars on one side and swinging them to line with the side bar on which they are pivoted. The carriage, when not in use, may thus be folded into a narrow compass vertically, in which condition it can be conveniently stored or transported.

What I claim as my invention, and desire to secure by Letters Patent, is—

In a perambulator, the combination, with the sides of the carriage-body, of a bottom piece hinged thereto and adapted to fold to the said sides, hinged links pivoted to the ends of the body-sides, whereby the said sides may fold to each other flatwise, and side bars carrying the axle-trees united by cross-pieces pivoted to one side bar and detachably connected to the other side bar, substantially as and for the purpose set forth.

HENRY COHENNO.
